DISPENSING CLOSURE FOR PASTE CONTAINERS

T. J. Duke Russell, 609 Las Lomas Ave.,
Pacific Palisades, Calif.

Filed Oct. 19, 1964, Ser. No. 82,217

Term of patent 14 years

(Cl. D58—26)

Fig. 1.

Fig. 2.

Fig. 3.

Fig. 4.

Fig. 5.

FIG. 1 is a top plan view of a dispensing closure for paste containers, showing my new design;

FIG. 2 is a bottom plan view;

FIG. 3 is a front elevational view;

FIG. 4 is a side elevational view; and

FIG. 5 is a perspective view.

I claim:

The ornamental design for a dispensing closure for paste containers, substantially as shown.
